DUMP BODY FOR A SMALL TRUCK
Roy F. Broyhill, Dakota City, Nebr. 68731

Filed July 23, 1970, Ser. No. 24,083

Term of patent 14 years

Int. Cl. D12—16

U.S. Cl. D14—3

FIG. 1

FIG. 2

FIG. 4

FIG. 1 is a side view of a dump body for a small truck showing my new design,

FIG. 2 is a back view thereof,

FIG. 3 is a front view thereof,

FIG. 4 is a bottom view thereof,

FIG. 5 is a top view thereof, and

FIG. 6 is a perspective view thereof shown in raised position relative to a small truck that is designated in broken lines for illustration only.

I claim:

The ornamental design for a dump body for a small truck, as shown and described.
